UNITED STATES PATENT OFFICE

FORREST A. WALKER, OF SYRACUSE, NEW YORK, ASSIGNOR TO WALKER DISHWASHER CORPORATION, OF SYRACUSE, NEW YORK, A CORPORATION OF NEW YORK

DISHWASHER

Application filed July 27, 1927. Serial No. 208,665.

This invention relates to a mechanical dishwasher in which a rotary impeller involving the use of a container for the dishes and washing fluid and suitable means for circulating a relatively small quantity of fluid upwardly and circumferentially within the container above the impeller and normal level of the washing fluid in a manner similar to that set forth in my pending application Serial 5 No. 124,640, filed July 24, 1926, so that the circulating fluid may impinge against the dishes in the trays or baskets and flow back 10 into the bottom of the container for recirculation.

15 These mechanical dishwashers are used in private and public kitchens, not only as separate units as shown in my pending application above referred to, but also in combination with sinks to be secured to the underside 20 of one or the other of the shelves or drain-board similar to that set forth in Patent No. 1,496,946, June 10, 1924, the object being to economize as far as possible in floor space in addition to the main function of economy of 25 time and labor, and conservation of water and power.

I have found that a relatively small electric motor is particularly well-adapted as the driving means for the rotary water-circulating impeller and that the cost of manufacture as well as the cost of operation may be kept comparatively low and the general efficiency of washing the dishes greatly increased if the impeller is constructed and 30 assembled in certain relations to the position and speed of the motor.

For example, the batch or batches of dishes operated upon at one time is necessarily limited to the ability and convenience of the operator in transferring the batches to and from the washing machine while the vat is constructed and arranged in such manner that a relatively small quantity of water, if properly circulated, will effect a thorough cleaning 40 of the dishes.

Furthermore, in this type of machine it is necessary to maintain a continuous propulsion of the limited quantity of washing fluid upwardly with a more or less concentrated 45 whirling motion and to allow the return flow

of the water to concentrate in and around the impeller for continuous recirculation and the main object of the present invention is to effect this result expeditiously and with a minimum power.

In other words, I have sought to construct the impeller so as to produce a maximum lifting and circulating force upon the liquid with a minimum amount of resistance under a speed of rotation and balance which will prevent excessive wear and strains upon the driving and driven elements.

Another object is to bring the motor and impeller into closer compact co-axial and direct-drive relation than has heretofore been practised so as to reduce the torsional and vibratory strains upon the driving shaft and impeller and thereby to obtain greater efficiency in the circulation of the washing fluid with a minimum amount of power.

A further object is to mount the motor directly upon a bushing in the bottom of the vat in such manner that the upright motor shaft will be supported entirely by the motor case irrespective of the bushing.

Another object is to provide the vat with a drainage outlet having a portion clamped between the motor case and bushing and to provide said outlet with a combination water level regulator and valve as a single unit adapted to be operated at will to open and close the valve for discharging the water from the vat or maintaining it therein as may be desired.

Other objects and uses relating to specific parts of the apparatus will be brought out in the following description.

In the drawings:—

Figure 1 is a longitudinal vertical sectional view of the lower portion of a mechanical dishwasher showing more particularly the manner of mounting the motor and drainage outlet upon the bottom of the vat and also the relation between the motor and impeller, the lower portion of the motor and upper portion of the vat being broken away.

Figure 2 is a horizontal sectional view taken in the plane of line 2—2, Figure 1.

Figure 3 is an inverted plan of the de-

tached cap for the water level regulator and drainage outlet conduit.

Figure 4 is a vertical sectional view on line 4-4 of Fig. 6 of the lower portion of a modified form of mechanical dishwasher in which the main body of the motor is shown in elevation while the upper portion of the vat and outer portion of the drainage outlet conduit are broken away.

10 Figure 5 is a side elevation of the detached impeller.

Figure 6 is a top plan of the impeller and underlying portion of the bottom of the vat.

In order that the invention may be clearly understood I have shown a portion of a conical bottom 1 of a vat adapted to receive the dishes and washing fluid, said conical bottom being provided with separate openings 2 and 3 arranged side by side in more or less close proximity, the opening 2 being formed in the apex of the bottom co-axial with the axis of the vat for receiving a bushing 4 while the other opening 3 is provided with a depressed conical peripheral wall to form a seat for a similar coniform head of a drainage outlet bushing 5.

The opening 2 and the bushing 4 are circular, the bushing 4 being provided with a more or less conical upper surface and an annular flange 6 resting upon the upper surface of the adjacent portion of the bottom 1, said bushing being also provided with an annular flange 7 fitting snugly within the opening 2.

The flange 7 is also provided with a plurality of, in this instance three, downwardly extending lugs 8 in uniformly spaced relation circumferentially and projecting some distance below the overlying portion of the vat 1 for receiving and supporting an electric motor 9 and a drainage conduit 10 in a manner presently described.

45 The opening 3 and drainage outlet bushing 5 are also circular, the bushing 5 being seated at its upper end snugly against the peripheral wall of the opening 3 with its upper face substantially coincident with the inner face of the adjacent portion of the bottom 1 and its lower end extending some distance below the bottom for receiving and partially supporting the drainage conduit 10 in a manner presently described.

The electric motor 9 comprises the main body 11 of the motor case and an upper case section or cap or motor supporting ring 12 having its lower end secured by bolts 13 or equivalent fastening means to the upper end of the case section 11 and its upper end secured to the lugs 8 of the bushing 4 by clamping screws 14 hereinafter more fully described, the 65 motor sections 11 and 12 being pref-

erably circular and arranged co-axial with the axis of the vat 1.

The drainage conduit 10 is provided with a horizontal extension 15 having a circular opening 15' therethrough co-axial with the axis of the vat 1 and adapted to receive the flange 7 of the bushing 4 and also the adjacent portion of the lugs 8 which together with the flanges 7 fit snugly against the peripheral wall of the opening 15' to hold the extension 15 and drainage conduit 10 against lateral displacement.

15 The upper end of the section 12 of the motor case is also provided with a circular opening 16' of substantially the same diameter as the openings 2 and 15' in the bottom of the vat 1 and extension 15 respectively so that the outer faces of the lugs 8 may fit snugly against the inner peripheral wall of the opening 16' and thereby to hold the motor in coaxial relation to the axis of the vat.

20 The top face of the section 12 is engaged with the underside of the extension 15 of the drainage outlet 10 so that the clamping screws 14 serve to hold the bushing 4 and adjacent portion of the bottom of the vat 1 together with the extension 15 and motor case section 12 against relative axial movement.

25 The lugs 8 are provided with inwardly tapered peripheral sockets 17 while the clamping screws 14 are provided with inwardly tapered inner ends adapted to engage in the tapered sockets 17 so that when tightened the tapered inner ends of the screws will engage the lower sides of the sockets 17 and thereby draw the bushing 4 downwardly until limited by the engagement of its flange 6 with the upper surface of the bottom of the vat 1 and at the same time forcing the motor case section 12 against the bottom of the extension 15 and simultaneously forcing the extension 15 against the bottom of the vat 1 for firmly holding those parts 30 against relative axial motion, it being understood that the distance between the axes of the sockets 17 and lower face of the flange 6 is somewhat less than the distance between the upper surface of the bottom of the vat 1 engaged by the flange 6 and axes of the screws 14 to allow a reasonable amount of take-up for wear of the walls of the conical sockets 17 and conical inner ends of the clamping screws and thereby to assure a firm clamping of the bushing 4, extension 15 and motor case section 12 to each other and to the bottom of the vat.

35 The bushing 4 is provided with a tubular post 18 extending upwardly therefrom into the interior of the vat 1 co-axial therewith and having its lower end 40

45 coaxial therewith and having its lower end 50

brazed or otherwise permanently secured to said bushing to form a part thereof.

As previously stated, the motor —9— is co-axial with the axis of the vat —1— and is provided with an armature shaft —19— extending upwardly therefrom through and above the tubular post —18— in spaced relation thereto to avoid frictional engagement therewith or with the bushing —4— so that 10 the shaft is supported entirely at its lower end by the bearing as —20— in the upper end of the motor case —1—, the purpose of which is to enable the motor —9— with the shaft —19— thereon to be placed in operative position upon the bushing —4— without making any special or laborious effort to maintain exact co-axial alinement of the bushing —4— and post —18— with the axis of the armature shaft as would be necessary if the shaft —19— had a bearing in the bushing or post.

A rotary impeller —21— is provided with a vertically elongated hollow hub —22— having its upper end closed and provided with an internal nut —23— rigid therewith, 25 said nut being screwed upon the reduced upper threaded end —24— of the shaft —19— to cause the impeller to rotate with the shaft and also to permit the impeller to be removed from the shaft when desired.

30 The hub —22— of the impeller extends downwardly from the top of the shaft —19— to a plane close to the upper face of the bushing —4— so as to surround said post but in spaced relation thereto to avoid friction 35 therewith whereby the impeller will be supported entirely from the upper end of the shaft, it being understood that the interior diameter of the hub —22— is somewhat greater than the external diameter of the post to afford the desired clearance.

40 The hub —22— is provided with similar blades —25— projecting laterally from diametrically opposite sides thereof and constructed with particular relation to the volume of water operated upon and also to the 45 speed of the motor requisite for producing the necessary upward lift and circumferential circulation of the water and also with particular relation to the angle of inclination of the conical bottom.

50 That is, the rotation of the impeller above certain speeds tends to displace the water from the center to the periphery of the vat and thence upwardly along said periphery with a more or less whirling motion but such a result would not be efficient in thoroughly washing the dishes in the trays or baskets which are usually supported in the vat in one or more planes above the impeller and it, 55 therefore, becomes necessary to construct the blades so as to enter the mass of water near the center with a minimum resistance and then to gradually lift the water and retard its centrifugal throw to such an extent as to 60 cause the main body of the water to be de-

flected upwardly with a more or less conical circumferential circulation and in order to accomplish this result the blades are elongated vertically and more or less spirally in reference to the axis of rotation so as to incline from their upper ends downwardly in the direction of rotation, the angle of inclination gradually increasing toward the lower ends of the blades so as to pick up the body of water near the center with a minimum resistance and then gradually deflect the same upwardly at a steeper angle to emerge from the upper ends in more or less fan-shaped streams which are carried circumferentially around the interior of the vat.

70 The portions of the lower ends of the blades adjacent the lower end of the hub are provided with laterally projecting flanges —26— inclining laterally and downwardly at a slight angle to a horizontal plane passing therethrough so as to enter the water with a minimum resistance as the impeller is rotated in the direction indicated by arrow —x—, Figures 5 and 6.

75 The diameter of the impeller is less than half the interior diameter of the vat at the normal level of the water therein as determined by a level regulator hereinafter described while the vertical height of the impeller is greater than the depth of the normal quantity of water in the vat so that the lower ends of the propeller blades of greatest angle of inclination project into the body of water while the upper ends of the blades project above the normal level of said body 80 but when the impeller is rotated the lower ends of the blades pick up the water with a minimum resistance and gradually forces the same upwardly along the inclined upper surface thereof until the water emerges from the upper edges of the blades in the form of fan-shaped streams which are carried around the entire area of the interior of the vat with considerable force to return by gravity to the bottom of the tub for recirculation.

85 The outer edges of the blades —25— are provided with flanges —25'— projecting forwardly in the direction of rotation at a slightly obtuse angle with the intermediate portions of the blades and extending from top 90 to bottom thereof for retarding the centrifugal throw of the water as the impeller is rotated, the obtuse angle of the flanges serving to assist in producing the fan-shaped streams emerging from the upper ends of the 95 blades while the upward lift of the water produced by the rotation of the impellers together with the upward momentum imparted to the water causes such water to pass through the trays and against the dishes with an upward circumferential motion to effect a thorough cleansing of the dishes by angular impact of the water therewith.

100 If desired, a soft packing ring —27— of rubber, felt or equivalent material may be 105

interposed between the nut —23— and outer end of the post —18— around the adjacent portion of the shaft —19— to prevent the passage of water upwardly through the open bottom of the hub —22— into the post —18— 5 and thence to the motor —9—, which, although such a condition is practically impossible without the use of the packing —27—, would be very detrimental to the motor in case 10 the water should pass for any reason from the interior of the vat into the tube —18—.

Water level regulator and drainage control

The drainage conduit —10— lies beneath 15 one side of the vat —1— and is provided intermediate its ends with an opening —28— in its upper side registering with the opening —3— in the bottom of the vat for receiving the lower end of the bushing —5— to which 20 it is clamped by screws —29— or equivalent fastening means accessible from the interior of the vat, said opening having an annular enlargement in its upper face provided with a conical peripheral wall —30— adapted to 25 engage the lower conical surface of the peripheral wall of the bottom —1— around the opening —3— through the medium of an interposed packing —30'—, Figure 1, to form a liquid-tight joint.

30 The outer end of the drainage conduit —10— is provided with an outlet —31— adapted to be connected to any available waste or soil pipe and having its peripheral wall tapered downwardly in the form of a 35 segment of a sphere to form a valve seat for a vertically movable valve and water level regulator —32—.

The valve seat or outlet —31— is disposed in a horizontal plane below the level of the 40 opening —3— in the bottom of the intermediate portion of the conduit which is inclined laterally and outwardly toward the outlet —31— to allow all of the water to be drained from the lowermost level of the interior of the vat.

The combination valve and liquid level controller —32— is tubular and disposed in an upright or vertical plane and has its lower end provided with a tapered peripheral surface 45 adapted to seat in the corresponding opening —31— when closed as shown in Figure 1, the upper end of the member —32— being provided with an upwardly flaring opening at a level some distance above the upper surface of the bushing —4— and in a 55 plane between the lower and upper ends of the impeller —21— or in a plane just above the level of the drainage opening —3— in the bottom of the vat —1— and is provided with a cross bar —33— to which is connected the lower end of an upright operating rod —34— having its upper end extending to a 60 suitable height for convenience of operation and provided with a handle —35— for that 65 purpose.

The portion of the conduit —10— adjacent the outlet —31— extends upwardly above the upper end of the member —32— when the latter is seated in the outlet —31— and is provided at its upper end with a cap section —36— held in place by screws —37— to form a guide for the rod —34—, said cap section —36— being provided with a central opening —38— through which the rod —34— extends.

75 The intermediate portion of the rod —34— adjacent the underside of the cap section —36— is provided with an annular groove —39— adapted to receive a pair of coiled springs —40— which are arranged on opposite sides of the rod and are connected at their opposite ends to suitable pins —44— on the underside of the cap section —36— for tensioning the coiled springs —39— against the periphery of the grooved portion —39— for frictionally holding the valve —32— in its extreme open position to permit drainage of the water from the vat —1—.

80 The valve operating rod —34— is preferably composed of sections —34'— and —34''— arranged end to end and coupled together by an internally threaded clamping nut —42— engaging the upper threaded end of the section —34'— and an enlarged flange —43— on the lower end of the section —34''—.

85 In the modified form of my invention shown in Figure 4 the bushing as —4'— is threaded externally and tightly screwed into an insulating sleeve —50— which is firmly secured in a central opening in the upper case section as —12'—, said bushing being 90 additionally clamped in place by a nut —51— engaged with the threaded portion thereof between the upper end of the case section —12'— and extension —15'— of the drainage conduit —10'—, the insulating —50— being extended between the adjacent faces of the nut —51— and upper motor case section —12'— as shown in Figure 4.

100 The conduit —10'— is provided with a downwardly projecting lug —52— adjacent one side of the motor case section —12'—, said lug having a threaded opening —53— for receiving a screw —54— which projects into an opening —55— in the adjacent side of the case section —12'— to hold the motor case and drainage conduit —10'— against 105 relatively angular movement.

110 The nut as —23'— in the upper end of the hub of the impeller —21— is preferably made of insulating material and secured directly to the upper end of the shaft for holding the impeller in operative position on said shaft to rotate therewith.

115 The insulations —50— and —23'— are placed in the positions shown to reduce the liability of short circuits or leakages of the motor-controlling circuits but may be dis- 120

125

pensed with as shown in Figures 1 to 3 inclusive.

Otherwise, this modified construction is substantially the same as that previously described and shown in Figures 1, 2 and 3, except that the diameter of the bushing is somewhat smaller than shown in Figure 1 and that a shield —56— is placed around the shaft —19— just below the top of the case section —12'— to deflect any water which may possibly, but improbably, pass into the interior of the tubular post —18— away from the armature of the motor, while the bushing —5— is screwed in place.

15

Operation

When placing the motor —9— in operative position the bushing —4— will first be inserted in the opening in the apex of the bottom of the vat —1— after which the extension —15— of the drainage conduit —10— is placed in operative position upon the bushing following which the motor —9— with the shaft —19— thereon will be placed from the bottom upwardly against the underside of the extension —15— and secured in place by the tightening of the screws —14— which, it will be noted, are accessible from the outside or periphery of the motor, it being understood that during this installation of the motor the shaft will be projected upwardly through the tubular post —18—.

When the drainage conduit —10— is placed in operative position in the manner just described, the peripheral walls of the annular enlargement in the upper face thereof will be brought into engagement with the peripheral wall of the opening —3— after which the bushing —5— may be inserted in the registering openings in the bottom of the vat —1— and top of the conduit —10— and secured in place by screws —29— which are readily accessible from the interior of the vat.

The propeller —21— may then be screwed upon the upper end of the shaft —19— and rotated with said shaft in the direction indicated by the arrows, Figure 6, by the operation of the motor —9— which may be controlled by any suitable switch in the motor circuit, not shown.

When the conduit —10— with the water level regulator and valve —32— therein is installed in the manner described and remains in its closed position, water may be introduced from any available source and in any desirable manner into the interior of the vat —1— and allowed to flow into the conduit —10— until it reaches the level of the top of the member —32— whereby the water will overflow through the member —32— and outlet as —31'— to the waste pipe not shown, thereby establishing a pre-determined level of the water in the vat which

cannot be exceeded beyond the level of the top of the closed member —32—.

When it is desired to drain the vat, it is simply necessary to lift the member —32— by means of its operating rod —34— to open the passage —31— and allow the water to drain from the vat through the opening —28— into the conduit —10— and thence outwardly through the openings —31— and —31'— to the waste pipe.

During the rotation of the impeller —21— the water is first picked up by the lower ends of the blades —25— and thereby deflected upwardly at the top of the blades in the form of fan-shaped streams which are given a whirling or circular motion by the force of upward propulsion and centrifugal force.

The centrifugal displacement of the water by the rotation of the impeller blades is retarded to a considerable degree by the flanges —25'— along the outer edges of the blades and by reason of their angular relation to the main bodies of the blades assist in forming the desired fan-shaped streams of water emerging from the upper ends of the blades when the impeller is rotated at the desired speed according to the vertical distance through which the water is obliged to travel and also the circumferential sweep of the streams of water depending, it being understood that the diameter of the propeller and form of the blades have a definite relation to the diameter of the vat at the normal water level.

It will also be noted that the motor shaft —19— which is also the impeller shaft is substantially free from frictional contact with any of the fixed portions of the vat or its bushing —4— and post —18— thereby establishing a freer rotation of the impeller than would be possible if the shaft were journaled in fixed bearings above the motor.

Another and most important advantage of this construction is that the motor armature shaft is brought close to the load or to the impeller —21— thereby reducing to a minimum the liability of torsional strains and vibrations of the impeller when rotated at sufficient speed to accomplish the desired lifting and circular motion of the water, all of which conserves the power required for operating the motor and also economizes in the use of water necessary for thoroughly washing or rinsing the dishes.

It is to be understood, of course, that after the dishes have been thoroughly washed and it is desired to rinse the same the fresh rinsing water may be introduced into the vat in which case the valve member —32— could be left open to allow the water to drain off as fast as it was introduced.

What I claim is:

1. In a mechanical dishwasher, a vat, an apertured bushing extending through an opening in the bottom of the vat and pro-

- vided with a flanged head engaging the inner
face of said bottom, a drainage conduit com-
municating with an opening in the bottom
of the vat and provided with an extension
loosely surrounding the portion of the bush-
5 ing adjacent the bottom of the vat, and a mo-
tor-supporting ring movably secured to the
lower end of the bushing and clamping the
conduit extension and bushing to the bottom
of the vat.
- 10 2. In a mechanical dishwasher, a vat hav-
ing a drainage outlet in its bottom, a bushing
secured in an opening in the bottom of the
vat at one side of the drainage outlet, a drain-
age conduit communicating with said outlet
15 and provided with an extension surrounding
the bushing, a motor supporting-ring oper-
atively mounted on the lower end of the bush-
ing for clamping the bushing and extension
20 to the bottom of the vat and movable means
for holding said ring in operative position.
3. In a mechanical dishwasher, a vat hav-
ing a conical bottom provided with an open-
ing in its apex, a bushing extending through
25 said opening and having its upper end rest-
ing upon the upper surface of the bottom
around said opening, a drainage conduit com-
municating with the interior of the vat and
provided with an extension surrounding the
30 bushing adjacent the underside of the bottom
of the vat, a motor-supporting ring having
its upper end surrounding the lower end of
the bushing and abutting against the under-
35 side of the extension of the drainage conduit,
and means for securing said ring to said
bushing.
4. In a mechanical dishwasher, a vat hav-
ing separate openings in the bottom thereof,
one of said openings being for drainage pur-
40 poses, a drainage conduit and a drainage
bushing engaging respectively the outer and
inner faces of the marginal walls of the drain-
age opening, adjustable means connecting
45 said conduit and bushing for tightening and
releasing the same, said conduit having an
integral apertured extension surrounding the
other opening and engaging the underside of
the walls thereof, a bushing engaging the
50 upper face of the marginal wall of the sec-
ond-named opening, a motor-supporting ring
adjacent the underside of the conduit ex-
tension around the aperture therein, and ad-
justable means connecting the bushing and
55 motor-supporting ring for holding the con-
duit extension and bushing in engagement
with the lower and upper faces of the mar-
ginal wall of the second-named opening.

In witness whereof I have hereunto set my
hand this 7th day of July, 1927.

FORREST A. WALKER.
